UNITED STATES PATENT OFFICE

2,516,869

COLLAPSIBLE TENT

Philip W. Harris, New York, N. Y.

Application June 17, 1946, Serial No. 677,150

12 Claims. (Cl. 135—1)

(Granted under the act of March 3, 1883, as amended April 30, 1928; 370 O. G. 757)

1 The invention described herein, if patented, may be manufactured and used by or for the Government for governmental purposes, without the payment to me of any royalty thereon.

This invention relates to a tent, and more particularly, to a collapsible tent which may be readily collapsed and folded into a compact form for portability.

The need for tents which may be quickly set up and readily dismantled for portability is recognized, especially for military use where it is necessary to shift camp sites rapidly and efficiently. It is therefore a major object of this invention to provide a collapsible tent which is simple, stable, efficient, comparatively light, and which may be set up or made portable in a minimum period of time.

It is another object of this invention to provide an improved tent having a flexible rib structure which may be quickly erected in the field to provide a rigid frame for the tent and without the use of poles.

A further object of this invention is to provide a collapsible tent having transverse and longitudinal ribs provided with hinges to enable the tent to be collapsed and folded at the hinges to provide a compact portable pack.

Still another object of this invention is to provide a collapsible tent having arched ribs, each rib being made up of members permanently hinged together and in which the members are of graduated lengths so that when the tent is collapsed the members may be successively folded at the hinges, commencing with the shortest member, to provide a compact package of substantially a cross-sectional rectangular form with a hollow interior, and which hollow interior may be used for storage purposes.

A further object of this invention is to provide a collapsible tent having a frame structure made up of short members hinged together and provided with a covering permanently fastened thereto, and in which cords are fastened to the covering in such manner that by merely pulling on the cords, the frame structure and covering will erect from a collapsed condition and thus the tent will be set up practically by a single stroke.

It is still a further object of this invention to provide a collapsible tent having hinged rib structure in which stops are associated with the hinges to limit pivotal movement of the rib members in one direction to form arches during erection and to permit free pivotal movement of the rib members in the opposite direction to permit

the tent to be folded into a compact pack for portability.

Still another object of this invention is to provide a tent provided with cords passing under the tent flooring for anchoring purposes, thus eliminating the need for anchor stakes driven into the ground.

A further object of the invention is to provide in a tent a flexible sheet, forming a tent wall or flap, and in which the flexible sheet is provided with expeditious means for quickly loosening and raising the flexible sheet to provide an opening in the tent.

Other objects and advantages of the present invention will appear in the following detailed description and particularly will be pointed out in the appended claims, reference being had to the accompanying drawings forming part of this specification and in which:

20 Fig. 1 is a perspective view of the collapsible tent of this invention;

Fig. 2 is a transverse sectional view of the interior of the collapsible tent and showing the front wall;

25 Fig. 3 is a transverse sectional view of the interior of the tent and showing the partly raised rear wall;

Fig. 4 is a plan view of the tent in collapsed condition with the front and rear walls in loosened and extended condition;

Fig. 5 is an exploded perspective view of the tent showing the ribbed frame structure, the flooring, and a portion of the covering;

30 Fig. 6 is a plan view of the partially folded tent showing the appearance after folding in a longitudinal direction;

Fig. 7 is a plan view of the tent in the process of being folded transversely after the longitudinal folds have been completed;

Fig. 8 is a perspective view of the tent pack, completely folded, and showing the flooring in the hollow interior;

35 Fig. 9 is a fragmentary detail of the hinged structure of one of the transverse ribs;

Fig. 10 is a diagrammatic view of a transverse rib in collapsed condition and showing a modified spacing for the hinges;

Fig. 11 is a diagrammatic view of the transverse rib of Fig. 10 in folded condition as it would appear in a pack and showing the square cross-sectional form when folded; and

40 Fig. 12 is a fragmentary perspective detail showing the use of flaps or tabs for covering the lacing openings.

Referring to the drawings, reference numeral 1 denotes the covering material, of canvas or other suitable material, which constitutes the roof and sides of the tent, and which covering is permanently fastened to the frame structure, denoted generally by the reference numeral 2, and clearly shown in Fig. 5. The frame structure is made up of a pair of transverse ribs 3 and 4 and a pair of longitudinal ribs 5 and 6 interconnecting the ends of the transverse ribs. As shown in Fig. 5, the longitudinal ribs 5 and 6 are each provided with two hinges 7, intermediate its ends, providing for a pair of short rib sections or members 8 and a long rib section or member 9 connected to constitute a continuous longitudinal rib. The transverse ribs 3 and 4 are each similarly provided with a plurality of flap hinges 10, thus providing for a plurality of transverse rib sections or members 11, 12, 13, 14, 15, 16, 17, and 18 connected to constitute a continuous transverse rib. The end rib members 11 and 18 are suitably rigidly fixed to the end rib members 8 of the longitudinal ribs. The ribs are preferably made of metal but wood or any other suitable material may be used within the scope of this invention. As indicated in Fig. 9, the transverse rib members 11 through 18, inclusive, are slightly arched and their ends are slightly beveled as at 19 so that when the members abut, the ends 19 become stops so that the rib members form a continuous rib of arch formation as shown in Fig. 5. However, it is within the spirit of the invention to have the members 11 to 18, inclusive, perfectly straight. Though the arch formed by a series of straight members will be somewhat imperfect, since the members are short as compared with the total length of the transverse rib, the arch will be sufficient for all intents and purposes. As clearly shown in Fig. 5, the members 11 through 18, inclusive, are of graduated lengths, for a purpose to be described hereinafter. Thus, as evident from this description and the showing in Fig. 5, the transverse rib members 11 to 18 may be pivoted downwardly about the hinges 10 until stopped by the stops 19 to assume the erected arched position as illustrated. Likewise, it is evident that, if permitted, the ribs 3, 4, 5, and 6 will collapse under their own weight and the weight of the tent covering 1 to assume a flat planar position of rectangular form in which ribs 3 and 4 constitute the sides of the rectangle and the ribs 5 and 6 constitute the ends of the rectangle. It is also evident that from this collapsed position, the longitudinal rib members 8 may be folded down on the rib member 9 by means of the hinges 7 to produce longitudinal folds, and then the transverse rib members 11 to 18, inclusive, may be successively folded about the hinges 10 to produce transverse folds so that an extremely compact package for portability will result. The length of each rib member and the number of members in each rib may be modified. For larger tents, more and/or longer members may be utilized, and for smaller tents, fewer and/or shorter members may be utilized.

As clearly shown in Fig. 5, the covering material is permanently fastened to the ribs 3 to 6, inclusive, by having the forward and rear edges 19 and 20 and the side edges 21 and 22 of the tent covering 1 folded back under the ribs for lapping the ribs and for stitching to the body of the tent 1. Other means of permanently securing the cover 1 to the frame structure 2 are within the purview of this invention. Each of the overlapped edges 19 and 20 of the covering 1 has

stitched thereto a strip of material 23 projecting downwardly and provided with spaced openings 24 for a purpose to be described hereinafter.

The front wall of the tent comprises a flexible sheet 25 of canvas, or other suitable material, cut to a substantially semi-circular formation to close up the open forward end of the tent. The upper periphery of the front wall 25 is provided with spaced openings 26 for alignment with the openings 24 for lacing the wall 25 to the strip 23 by means of lacing 27. As shown in Fig. 1, when the tent is erected, the lacing 27 extends around the upper periphery of the front wall and with its free ends passing through the loop straps 28 and 29 secured to the bottom of the front wall 25. The free ends of the lacing 27 are tied together, as at 30, to prevent accidental unlacing. Intermediate the free ends of the lacing 27 there is provided a release cord 31, to be described hereinafter, fixed to the lacing at 31' as shown in Fig. 5, and having its free end fastened to or guided through the loop strap 32. The front wall 25 is provided with a door flap 33 secured on one or two sides in any suitable manner, as by stitching, and held in closed position by means of tie strings 34. On the interior, adjacent the upper end of the front wall, there are fixed a pair of pulleys 35 for a purpose to be described hereinafter. The rear wall 25' is constructed and secured as the front wall 25 except that the door flap 33 may be omitted. To reinforce the corners of the tent covering 1, corner gussets 36 may be provided.

As shown in Fig. 5, the tent may be provided with a floor construction consisting of a number of sections or panels 37 placed side by side to form a row, and two such rows are illustrated. The number of sections or panels in each row and the number of rows shown in Fig. 5 are merely representative, and are in no way to be considered as limiting the invention. The floor panels 37 are each provided with one or more joists 38, providing for a raised floor construction. As shown, each floor panel 37 is of greater length than its joist 38, providing for overlaps at the ends, as at 39. These overlaps provide three transverse channels under the flooring, at the front, center, and rear, for a purpose to be described hereinafter.

The covering 1, as clearly shown in Fig. 5, is provided with the cords 40, 41, and 42, each having one end suitably secured to the side edge 22 of the covering at points 43, 44, and 45, respectively. The free ends of the cords 40, 41, and 42 are adapted for passing through the openings 46, 47, and 48, respectively, in the side edge 21 of the covering 1. The longitudinal rib 5 is provided with openings 49, 50, and 51 in alignment, respectively, with the openings 46, 47, and 48 so that the free ends of the cords 40, 41, and 42 are adapted to pass also through the rib 5. The free ends of the cords 49 and 41 are preferably each provided with a stop element 52, tied to the free end, to prevent the free end of the cord from being pulled through the respective openings 46 and 47. A large knot in the free end of each of cords 49 and 41 may be utilized instead as a stop element.

In assembling the tent, assuming the parts are in the collapsed position shown in Fig. 4, it is merely necessary for the operator to grasp the free ends of the cords 40 and 41, and while holding the side edge 21 of the tent, to pull on the free ends of the cords. This action will bow the transverse ribs 3 and 4 upwardly while the far side edge 22 of the tent is drawn towards the

side edge 24. Two men can pull on the cords 40 and 41 simultaneously to arch both the front rib 3 and rear rib 4, or one man can successively erect the front and rear arch by pulling on one cord after the other. After the ribs 3 and 4 have been arched sufficiently, as indicated by a red mark, which may be placed on each cord, appearing through the openings 46 and 47, the flooring, if used, may be positioned within the tent with the front and rear overlaps 39 being placed over the cords 40 and 41 extending on the ground. While the flooring is being set in position, the free ends of the cords 40 and 41 may be temporarily fastened to the loop straps 53 and 54, respectively, to maintain the arch. In placing the flooring, care should be taken to have the center overlap 39, between the two rows of flooring, positioned over the center cord 42. Then with the flooring in place, continued pulling of the cords 40 and 41 will draw the longitudinal rib members 5 and 6 against the sides of the flooring in a vice-like manner, thus producing a rigid structure. When flooring is not used, the cords 40 and 41 may be pulled initially to arch the ribs to final position. In final position, the free ends of the cords 40 and 41 may be secured to the loop straps 53 and 54, fastened on the side of the tent. The center cord 42, having its free end passing through opening 48, is drawn tight and its free end is secured to the loop strap 55, clearly shown in Fig. 1. It can be seen from this structure that when flooring is used, the cords 40, 41, and 42 passing under the overlaps 39 of the flooring provide an anchor means for the tent whereby the tent is securely anchored to the flooring without the need of stakes or other securing means fastened or driven into the ground. Thus, the condition of the ground will not affect the tent of this invention, and the tent may be erected on hard ground, such as coral, or on loose sand, and still be anchored securely. The arched ribs of this invention provide a sturdy upright construction and no poles are necessary to maintain the tent erected.

In order to collapse and fold the tent for moving to another site, it is merely necessary to untie the lacing knot 30 at the front and rear walls, and pull on the front and rear release cords 31. The sudden pull on each release cord 31 will cause the cord 27 to be pulled through the openings 24 and 26 and the free ends of the lacing 27 will be completely freed from the lowermost openings 24 and 26, as shown in Fig. 4. The number of openings to be freed will depend on the spacing of the openings but a sufficient number should be freed to enable the walls to be stretched flat, as described hereinafter. After the front and rear walls have been loosened in this manner, it is merely necessary to untie the free ends of the cords 40, 41, and 42 and under the weight of the tent, the structure will collapse as the arched ribs straighten as indicated in Fig. 4. By holding on to the free ends of the cords 40 and 41, the collapsing may be regulated so as to be gradual. When flooring is used, the tent should first be partially collapsed until the red marks on the cords 40 and 41 reach the openings 46 and 47, and then with the free ends of the cords 40 and 41 temporarily tied to the loop straps 53 and 54, the flooring may be removed. Then after completely collapsing, the front and rear walls should be extended into a flat form with the lacing 27 loose, as shown in Fig. 4. From the position of Fig. 4, the front and rear walls then should be folded under the tent, as indicated by dotted lines in

Fig. 4. The transverse ribs 3 and 4, that is, the front and rear edges 19 and 20 of the tent, then should be lifted and pivoted in a longitudinal direction about the hinges 7 so that the tent assumes the semi-folded position shown in Fig. 6. Then the semi-folded tent is inverted and rolled in a transverse direction, as indicated in Fig. 7, by starting with the rib member 11 and folding each rib member from 11 to 18, inclusive, successively 90° to produce a box like pack as shown in Fig. 8. The front and rear cords 40 and 41 are rolled in the pack during this step but the center cord 42 then is wound about the rolled pack and fastened to the loop member 55 to lock the pack in the form shown in Fig. 8. The hollow space within the pack then may be utilized to receive the stacked flooring, as denoted in Fig. 8. However, it is within the purview of this invention to transport the flooring by other means and to utilize the hollow space for other storage purposes or not at all.

In order to provide for a tent pack having a substantially square cross-section, it is merely necessary to change the dimensions of the graduated members 11 to 18, inclusive, and this is clearly shown in Fig. 10 wherein the members 11 to 18 are arranged to provide a bundle of square cross-section when folded, as shown in Fig. 11. It is also within the scope of this invention to provide for packs having a triangular cross-section.

When it is desired to raise the front or rear walls 25, 25' for ventilation or otherwise, it is merely necessary to tug on the release cord 31 to free the ends of the lacing 27 from the lowermost openings 24 and 26 and then loop the free ends of the lacing under the bottom edge of the wall and carry said free ends through the pulleys 35. Then by pulling on the free ends of the lacing, looped through the pulleys, the bottom edge of the wall will be rolled up as shown in Fig. 3. The front and rear walls may be kept down, partially down, or up, depending on the weather.

After the wall is raised, the free ends of the lacing may be secured to the strip 23.

If desired, to provide for maximum shelter, the lacing openings 26 may be covered by means of swivel tabs 57, as shown in Fig. 12, which may be pivotally secured to the wall 25, 25', as at 58, and rotated to cover the opening 26.

It is apparent that a tent has been provided which includes a frame structure and a covering permanently attached thereto so that when the frame is set up, collapsed or folded, the covering is automatically taken care of, requiring no separate handling. Also, it is apparent that the tent, including frame and covering, is substantially erected by almost a single stroke, that is, by a pull on the cords 40 and 41. This feature coupled with the folding character of the collapsed tent, both in a longitudinal and transverse direction, provides for ready portability of the tent. Also, the storage space formed in the folded tent package affords a ready means to transport the tent flooring with the tent.

Although the tent illustrated is provided with hinged transverse ribs for arching, it is within the scope of this invention to also utilize unitary flexible bars as the transverse ribs. These bars can be arched for erection due to their flexibility. In this modification, however, the tent will not be folded transversely as with the hinged transverse bars.

Although the tent illustrated has a semi-circular cross-section, it is within the purview of this invention to provide for other shapes. For example, the tent can be made flatter on top, with sides more nearly vertical. This may be accomplished by thickening the center portions of the transverse flexible ribs to produce a flatter top portion when erected. Also, where hinges are used, the angle of the stops 19 may be varied so that at the center of the transverse ribs, the rib members will lie flatter when erected.

While the invention has been described in more or less detail, it is not to be limited thereby, as changes may be made in the form, arrangement and construction of parts, and equivalents may be substituted, without departing from the spirit and scope of the invention as claimed, the form hereinbefore described being merely a preferred embodiment thereof.

I claim:

1. A collapsible tent frame comprising arch-shaped transverse ribs and flat longitudinal ribs connected to the ends of the transverse ribs, each of said ribs composed of a plurality of permanently and hingedly-connected sections.

2. A collapsible tent frame comprising arch-shaped transverse ribs and flat longitudinal ribs interconnecting the ends of the transverse ribs, each of said ribs composed of a plurality of permanently and hingedly-connected sections, the hinge connections of the sections limiting pivotal movement thereof in one direction into substantial alignment and permitting pivotal movement in the other direction into folded relationship.

3. A collapsible tent frame comprising arch-shaped transverse ribs and flat longitudinal ribs connected to the ends of the transverse ribs, each of said ribs comprising a plurality of sections, and hinges connecting said sections with their ends in abutting relationship when the frame is set-up but leaving the sections free to swing about their hinges to collapse the frame.

4. A collapsible tent frame in the form of a rectangle when partly collapsed, each of the sides and ends of the frame composed of hingedly-connected sections, and a rigid connection between the ends of the sections constituting the respective corners of the frame.

5. A collapsible tent frame in the form of a rectangle when partly collapsed, each of the sides and ends of the frame composed of a plurality of sections, flap hinges connecting the sections of the ends of the frame in abutting relationship, and other flap hinges connecting the ends of the sections of the sides of the frame with the ends of the sections slightly spaced apart when the frame is in its partly collapsed condition.

6. A collapsible tent frame in the form of a rectangle when partly collapsed, each of the ends of the frame composed of a central section and end sections hingedly-connected to the central section, each of the sides of the frame composed of a plurality of hingedly-connected sec-

tions, the adjacent ends of the sides and ends of the frame being rigidly connected.

7. A collapsible tent frame in the form of a rectangle when partly collapsed, each of the ends of the frame composed of a central section and end sections hingedly-connected to the central section, each of the sides of the frame composed of a series of hingedly-connected sections of gradually increasing length, and means rigidly connecting the adjacent ends of the sides and ends of the frame.

8. A collapsible tent frame in the form of a rectangle when partly collapsed, the sides of the frame composed of a plurality of slightly curved sections hingedly-connected together, the ends of the frame composed of a plurality of flat sections hingedly-connected together, and rigid connections between the adjacent ends of the ends and sides of the frame.

9. In a collapsible tent frame a foldable arch-shaped rib or bow comprising a plurality of hingedly-connected sections having their hinged ends in abutting relationship when the rib is in set-up condition.

10. A collapsible tent comprising a frame including arch-shaped transverse ribs and flat longitudinal ribs connected to the ends of the transverse ribs, each of said ribs composed of a plurality of permanently and hingedly-connected sections, and tent material having its edges attached to said frame.

11. A collapsible tent frame formed of arch-shaped transverse ribs and flat longitudinal ribs interconnecting the ends of the transverse ribs, each of said ribs composed of a plurality of sections, flap hinges connecting the adjacent ends of the section of each rib, the hinge connections of the sections limiting pivotal movement of the sections in one direction into substantial alignment and permitting pivotal movement in the other direction into folded relationship, and releasable means connecting the longitudinal ribs.

12. A collapsible tent comprising a frame formed of arch-shaped transverse ribs and flat longitudinal ribs connected to the ends of the transverse ribs, each of said ribs composed of a plurality of permanently and hingedly-connected sections, tent material having its edges attached to the frame, and releasable means connecting the longitudinal ribs.
